GAS FLOW CONTROL SYSTEM

Norman S. Strandwitz, Chicago, Francis J. Eichelman, Brookfield, and William E. Doering, Chicago, Ill., assignors to National Cylinder Gas Company, Chicago, Ill., a corporation of Delaware

Application October 29, 1952, Serial No. 317,534

10 10 Claims. (Cl. 62—1)

This invention relates in general to a gas flow control system, and more particularly, to a gas flow control system serving a consumer supplied from alternately replenishable banks of cylinders or other supply sources under relatively high pressure and wherein a uniform flow at a relatively low constant pressure is the desideratum. A consumer having such a need may generally be found in a hospital having an internal gas piping and distributing system and using large quantities of a gas, such as oxygen, for medical purposes.

In such installations, the consumer's piping and distributing system is generally supplied with gas from a group or groups of cylinders manifolded together and known as the service supply, with a second or reserve supply of manifold cylinders connected and in readiness to supply the system when the service supply becomes exhausted and while it is being replenished. The former reserve supply then becomes the service supply and when the exhausted source has been replaced by fully charged cylinders, it then becomes the stand-by or reserve supply. In many gas consuming installations, this change over may be accomplished manually by the reversal of a simple T valve or the like between the service and reserve supplies and the line when the imminent exhaustion of the service source is observed. However, in an installation such as a hospital, where lives may be dependent on a continuous and uniform flow of a gas, such as oxygen, a simple manual switching system subject to human error cannot and should not be relied on to the extent inherently necessary. Accordingly, particularly for hospital installations, it has been known to provide a pair of interconnected pressure reducing valves or regulators each associated with one of the banks of cylinders or other supply sources and differentially pre-set to automatically change over from the service supply to the reserve supply when the pressure in the service supply fell to a near exhaustion pressure and lower by the differential amount than the presetting of the service regulator, and to then give an appropriate alarm announcing that condition. Although such an automatic change over is an improvement over reliance upon human observation and manual operation, the systems heretofore provided had the serious disadvantage of being subject to a pressure drop in the line from the desired line pressure when the service supply was approaching exhaustion and prior to the automatic change over to the reserve supply. After the change over occurred, it was accompanied by an equally disadvantageous surge or increase in the line pressure up to the desired line pressure when the second regulator of the pair was reset, as was obviously required in such cases.

The system of this invention overcomes all of the disadvantages inherent in previously known expedients and is capable of maintaining a completely uniform line pressure notwithstanding a differential setting of the pair of automatic change over controlling regulators. Furthermore, it provides means where if either of the differentially set change over regulators should become inoperative,

2

5 tive, the remaining regulator of the pair and a line regulator can be utilized to maintain a uniform flow from either of the alternate supply sources to the consumer's system while the inoperative regulator is repaired or replaced. Likewise, if one of the pair of change over regulators and the line regulator both become inoperative, the single remaining regulator can maintain a uniform flow pressure.

10 Accordingly, it is the principal object of this invention to provide an automatic change over flow control arrangement whereby a steady and uniform flow of gas to the consumer's installation is maintained notwithstanding that one or more of the regulators of the system may be out of order or become inoperative.

15 Another object of the invention is to provide a simple and foolproof gas flow control system which does not require the services of a mechanically skilled attendant, and may be operated easily by anyone. It will be apparent that this feature is of great benefit in hospital installations.

20 It is a further object to provide a uniform gas flow control arrangement which is tamperproof, and which has an inherent high degree of safety and dependability in operation so that under no circumstance will the uniform flow of gas be interrupted.

25 Another object of the invention is to provide a simple mechanical reset mechanism so that after an automatic change over of supply source, the differential settings of the linked regulators may be easily reversed without internal adjustment.

30 An outstanding feature of the invention resides in its compact arrangement whereby it can be readily encased in a locked cabinet with only a reset lever and three piping connections extending therefrom so that the entire flow control arrangement can be made substantially tamperproof.

35 Additional features and advantages will become apparent as the following description proceeds particularly taken in conjunction with the accompanying drawings wherein:

40 Fig. 1 is a diagrammatic showing of a preferred embodiment of uniform gas flow control system provided by this invention;

45 Fig. 2 is a plan view of a portion of the system of Fig. 1 particularly showing the manner in which the differentially set change over regulators of the system are linked and the means whereby the reversing of the differential settings may easily be accomplished in the reset operation; and

50 Fig. 3 is a sectional view on line 3—3 of Fig. 2.

55 Assuming that a right hand bank of manifolded gas cylinders or other high pressure supply source (not shown) is considered the service supply for the purposes of illustration, the invention is best described by tracing the flow of gas in Fig. 1.

60 Gas, such as oxygen, at relatively high pressure from a full supply source, such as a bank of manifolded cylinders, under an initial pressure in the range of 2400 to 2600 p. s. i., depending upon the size and construction of the supply source, flows through right hand header 10 and normally open valve 11. As by-pass valve 12 is normally maintained closed unless a special condition arises which will be described later, the gas from the right hand supply source, presently considered the service supply, flows through another valve 13, high pressure reducing valve or regulator 14 and check valve 15 into a delivery header 16, which may also be a hollow mounting block or bar. The high pressure reducing regulator 14 is preset to deliver on its outlet side, that is, through the check valve 15, to header 16, gas under a reduced pressure, which for the purposes of illustration may be considered to be 80 p. s. i. At the same time a left hand high pressure

65 70 75 80

supply source, such as a second bank of manifolded gas cylinders (not shown) connected to left hand header 17, may be considered for the purposes of illustration as the reserve gas supply. Left hand valves 18 and 19, like the corresponding right hand valves 11 and 13, are normally open so that if there were no restraining circumstance, gas would also flow from this supply through high pressure reducing valve or regulator 20 and check valve 21 to the header 16. However the regulator 20 is preset to deliver gas on its outlet side at a constant pressure somewhat below the delivery pressure for which the regulator 14 is preset, for example, at 70 p. s. i. Thus, there exists a differential of 10 p. s. i. between the delivery pressure of the two regulators 14 and 20. In general, a pressure differential between these regulators should be at least 5 to 7 p. s. i., and a differential in the neighborhood of 10 to 12 p. s. i. is preferred. Both regulators 14 and 20 are conventional high pressure reducing regulators and may be either single or double stage, stem or nozzle types, or a combination of these, all of which types of regulators are well known. Preferably, these high pressure reducing regulators are of the type disclosed in copending application Serial No. 778,939, filed October 9, 1947, now Patent No. 2,651,147 issued September 8, 1953. Regardless of the specific type of regulators provided, the pair of regulators 14 and 20 constitute the differentially preset automatic change over mechanism of the system.

In view of usual regulator construction, as well as the construction of the preferred type of regulators shown in copending application Serial No. 778,939, the fact that regulator 20 is preset to deliver gas at a pressure lower than that delivered by regulator 14, precludes the flow of gas from the left hand or reserve supply until the regulator 14 is no longer able to maintain its constant delivery pressure due to the near exhaustion of the right hand supply source with consequent reduction of its pressure to a value below the present delivery pressure of regulator 20. In the embodiment here illustrated, this would mean that no gas will flow from the reserve supply into header 16 until the pressure in the service or right hand supply has diminished to 70 p. s. i., at which time the delivery of gas at 70 p. s. i. pressure from the reserve supply to header 16 will immediately commence through regulator 20, as will be described more fully subsequently. Meanwhile, gas from the service or right hand supply is being delivered to the header 16 at a constant pressure of 80 p. s. i. and because of check valve 21 and the inherent non-reversible flow construction of pressure reducing regulators in general, as well as the full higher pressure in the reserve supply, no reverse flow of gas toward the reserve supply can occur. The gas from the service supply, therefore, flows from header 16 through valve 22, which is normally open, line regulator 23, check valve 24 to consumer's line 45 as indicated in Fig. 1. A secondary by-pass valve 25 is normally closed so that the gas follows the path just traced and does not flow through secondary by-pass piping or conduit 26. The secondary by-passing piping 26 is coupled into the flow path just described up-stream of check valve 22 by means of a T connection 27 and into the consumer's line 45 downstream of check valve 24 by means of a cross connection 28, for the purpose of providing a by-pass flow of the gas in the event that line regulator 23 is in need of repair or is being replaced.

There is further provided at the cross connection 28 down-stream of check valve 24, a relief valve or safety release 29, which should preferably be vented to the open atmosphere. This relief valve 29 may be preset at any desired release pressure depending on the apparatus in the installation which it is designed to protect as well as on the final line pressure setting for which regulator 23 is preset.

Regulator 23 may again be any type of conventional gas pressure reducing regulator but is preferably a line type regulator; that is to say, it is designed merely to

further regulate an already reduced, relatively low delivery pressure from a high pressure regulator, such as either 14 or 20. For purposes of illustration, it may be assumed that line regulator 23, which may be either single or double stage, nozzle or stem type, is in fact a stem type, single stage, line regulator designed for an approximate inlet pressure of not more than 300 p. s. i. and in the embodiment here being described is preset to deliver a constant outlet or line pressure to the distributing system in the neighborhood of 50 to 60 p. s. i. It will be seen, therefore, that regulator 23 in the illustrated example is not required to regulate or to reduce pressures through a range greater than about 20 to 30 p. s. i., since as has already been described, regulator 14 is preset to deliver 80 p. s. i. and the outlet delivery pressure of line regulator 23 normally would not be less than 50 p. s. i., particularly in hospital installations. The flow of gas from the service supply thus traced will continue at a constant delivery pressure until the service or right hand supply becomes substantially exhausted, or when the gas pressure at the supply source is diminished to 70 p. s. i. or less. At this point regulator 20, which thus far has been considered the reserve supply regulator, automatically takes over and begins delivering gas to the header 16 at its preset delivery pressure of 70 p. s. i. Gas from this source then follows the same flow path previously described through the T 27, valve 22, line regulator 23, check valve 24 and cross connection 28 to the line 45. It will be noted that the all-important factor of continuous flow of gas at constant pressure to the installation is thus maintained by the operation of line regulator 23, notwithstanding any slight variation in gas pressure delivered to header 16. Therefore, in an installation, such as a hospital, the essential requirement of a constant flow of oxygen is constantly maintained at a uniform, steady line or flowing pressure without manual manipulation.

As the pressure from the right hand or service supply drops from 80 to 70 p. s. i., the pressure in header 16 also diminishes until it also reaches the pressure (70 p. s. i.) at which the left hand or reserve supply is automatically put into service. A mercury contact pressure gauge 30, preset to close an electrical circuit when the pressure in header 16 falls to the predetermined pressure, here 70 p. s. i., then operates to close the circuit at its contacts schematically shown at 31, lighting an incandescent lamp 32 from any suitable power source generally indicated at 33. It will be understood that power source 33 is shown in the drawing as a battery only for purposes of illustration, and may equally well be a power tap to the available electrical supply line at the installation.

When lamp 32 is lit, it operates as a signal to indicate that the service supply of gas has become exhausted, and that the installation is being served by the reserve supply. Other indicia (not shown) may also be provided which, when the lamp 32 is lit, simultaneously become visible or audible, or both, in various locations as desired. Such indicia may preferably comprise lighted instructions to be then followed by service personnel. For example, it would be necessary to arrange for replenishment of the right hand supply source of gas, and thereupon it is merely necessary to move reset lever 35 to its opposite or remote position. This latter action automatically and instantaneously resets change over regulator 20 to the higher differential pressure of 80 p. s. i. used in this example, and the right hand change over regulator 14 is by the same action reset to the lower delivery pressure of 70 p. s. i. The left hand source then becomes the service supply and, when replenished, recharged, or replaced, the right hand source becomes the reserve supply. As noted briefly before, the gas from the left hand supply (now the service supply) cannot flow back into or equalize with the exhausted supply source because of the check valve 15 and the inherent nonreversible flow construction of gas pressure reducing regulators. Moreover,

as soon as the reset lever 35 has been moved, thus resetting regulator 20 to the higher delivery pressure and thereby increasing gas pressure to the header 16, the mercury contact pressure gauge 30 operates to open the signalling circuit so that the lamp 32 is extinguished, and other indicia returned to normal. The operation then continues using gas from the left hand supply until it becomes depleted to a pressure of 70 p. s. i., whereupon the replenished right hand reserve supply automatically goes on stream in the manner previously described, and with no delay and no loss of line pressure to the installation. In this manner, the operation continues with the supply sources being alternated from service to reserve status as they are alternately depleted and replenished with only the reset lever 35 being moved from its one extreme position to the other when the exhausted supply source is replenished.

The instantaneous readjustment and reversal of the differential pressure setting of the change over regulators 20 and 14 is accomplished by movement of reset lever 35 as is illustrated in Figs. 2 and 3, and described in detail hereinafter. In the case of all conventional gas pressure regulators the delivery pressure from the regulator is diminished by rotating their adjusting screws counterclockwise, and reverse rotation serves to increase the delivery pressure. The regulators 14 and 20 are arranged with their adjusting screws 36 toward each other as shown in the enlarged view of that portion of the system shown in Fig. 2, and the free ends of these adjusting screws 36 of both regulators 14 and 20, instead of terminating in a conventional hand wheel are each provided with a nut 37, which in the embodiment illustrated is hexagonal. A reset lever sleeve 38 which is internally broached to a complementary hexagonal shape that fits closely over the ends 37 of the regulator screws 36 is provided to link the free ends 37 of the regulator adjusting screws 36. Suitable securing means, such as set screws 39, are provided to hold the sleeve 38 in place. A suitable lever arm 40 of the reset lever arrangement 35 is secured in any suitable manner, such as by silver soldering, at joint 41 to the sleeve link 38, and the outer or free end of the lever arm 40 is provided with a knob 42. When the reset lever 40 is rotated, obviously one regulator adjusting screw 36 will be rotated clockwise and the other counterclockwise. The regulators are adjusted so that a single movement, of for example, through an arc of 90°, of reset lever 35 will respectively raise and lower the preset delivery pressure by the desired differential value, thereby reversing the preselected delivery pressures of regulators 14 and 20. Thus, with lever arm 40 in its down position (Fig. 1), the regulator 14 as has been described in the example for illustration, delivered a pressure to header 16 higher by the desired differential value than that deliverable by the regulator 20 due to the preselected initial adjustments of the two regulators. After the right hand supply source has been replenished, lever 40 of the reset arrangement 35 is moved to its opposite or up position whereby adjusting screw 36 of the regulator 14 is rotated counterclockwise diminishing its delivery pressure setting while adjusting screw 36 of the regulator 20 is rotated clockwise thereby increasing its delivery pressure setting. The converse action occurs after the left hand source is replenished. It will therefore be seen that this simple movement of lever arm 40 from one position to the other effectively reverses the delivery pressure adjustments of the regulators 14 and 20.

The entire arrangement is sufficiently compact so that it may be easily encased in a cabinet provided with a slot in its face through which the reset lever arm 40 extends. The slot may be of such a length that it is only possible to rotate the lever 40 through an arc of about 90°. The cabinet may also be arranged so that only the conventional pressure gauges (not shown) of regulators 14, 20, and 23 are visible from the outside of the cabinet and

with reset lever arm 40 appear on the face of the cabinet. The pressure gauges of regulators 14 and 20 will always indicate the pressures of their respectively associated supply sources and the gauge of regulator 23 will indicate the line pressure at which the gas is being supplied to the installation. Furthermore, the only members other than reset lever 40 which extend outside of the cabinet are suitable header connections for supply headers 10 and 17, and the line 45 to the distributing system of the installation.

Within the cabinet, and not visible from the outside, there are provided a service pressure gauge 43 and a service valve 44 connected into header 16. The service gauge 43 and service valve 44 are provided for the convenience of service personnel in the event that one of the elements, such as a regulator, fails to function properly. Furthermore, the various valves, such as valves 11, 12, 13, 18, 19, 22 and 25, whose functions have not previously been described, may be enclosed within the cabinet so that should one of the automatic change over regulators 14 or 20, for instance, or line regulator 23, fail to function, or should both line regulator 23 and one of the change over regulators 14 or 20 become inoperative, the unit may be temporarily adjusted to enable the remaining regulator or regulators, as the case may be, to continue to supply the installation without interruption or pressure change while the necessary repair or replacement is made.

Assuming that the left hand supply is operating as the service source and regulator 20, preset to deliver 80 p. s. i., begins to deliver an increased pressure due to a defect, line regulator 23 will maintain a uniform pressure and flow of gas to the line 45 despite higher pressures at its inlet side. In this case service gauge 43 on inspection of the system will reveal the increased pressure delivered by regulator 20 to header 16, and valves 19 and 11 may then be closed while by-pass valve 12 is opened, although not necessarily in the order named, whereby gas from the service supply is by-passed through valve 12 and the by-pass conduit in which it is located, and through valve 13 to regulator 14. Valve 11 is closed to prevent gas from the reserve supply source, which normally will be at a higher pressure than the operating supply, from equalizing with the partially depleted service supply when the by-pass valve 12 is opened. Regulator 20 may now be removed with no loss of gas from header 16 because of the check valve 21. The regulator 20 thus may be inspected, repaired or replaced while regulator 14 serves the system from the left hand source via header 16 and line regulator 23. If the left hand supply becomes depleted while this situation prevails, the by-pass valve 12 may be closed and valve 11 opened whereupon regulator 14 will serve the system from the right hand supply. Alternatively, by-pass valve 12 may remain open if both valves 18 and 19 are closed. It will be observed therefore, that in an emergency, either of regulators 14 or 20 can operate individually from either source without interruption of service to the system.

Before the regulator 20 is returned to service, the delivery pressure from regulator 14 may be ascertained by momentarily bleeding gas from the header 16 through service valve 44 and observing service gauge 43. If necessary or desirable, adjustment may then be effected by means of adjusting screw 36 of regulator 14. Regulator 20 may then be returned to service by closing the by-pass valve 12 and opening valve 19. The delivery pressure of regulator 20 likewise can be determined after a momentary bleeding of the header 16 through service valve 44, and if necessary, regulator 20 can be adjusted before the reset lever linkage sleeve 38 is secured in place.

Conversely, in the event that regulator 14 malfunctions, gas from the right hand supply can be by-passed to the regulator 20 by a corresponding manipulation of the valves, that is, by closing valves 18 and 13 and opening by-pass valve 12. The regulator 14 may then be re-

moved, while check valve 15 prevents loss of pressure in header 16.

Similarly, in the event that line regulator 23 becomes inoperative, or fails to function, valve 22 may be closed and secondary by-pass valve 25 opened so that regulator 23 may be removed, repaired or replaced. The supply of gas to the line 45 continues and the system remains closed by means of check valve 24. If the installation is such as to require that the line pressure be maintained at not more than 50 p. s. i., it is only necessary that one of the regulators 14 or 20 be suitably adjusted prior to the opening of secondary by-pass valve 25. The other of regulators 14 and 20 is then precluded from operation by closing either valve 13 or 19 as the case may be. The thus adjusted regulator of the change over pair, either 14 or 20, will then temporarily deliver gas at the desired line pressure until the line regulator 23 is returned to service.

In the event that both of regulators 23 and 20 or both of regulators 23 and 14 become simultaneously inoperative, the remaining regulator, either 14 or 20, may be employed to maintain uniform, uninterrupted delivery of gas to the system by appropriate manipulation of the valve system described. It will therefore be apparent that short of a complete breakdown, which is exceedingly unlikely by reason of the arrangement described, a continuous, uniform and uninterrupted flow of gas may be maintained to the distributing system at all times, and with a high degree of flexibility in operation.

It will be understood that this invention resides in the novel combination, arrangement and adaptation of parts and that such modifications as will suggest themselves to those skilled in the art and which come within the spirit of this invention are included within its scope as defined by the appended claims.

We claim:

1. In a gas flow control system for maintaining a uniform flow of gas at predetermined pressure from a plurality of alternate sources at varying higher pressures wherein a pair of high pressure reducing regulators adjusted to deliver gas at pressures differing by a preselected differential value and each of which is connected to at least one of said sources through a common header to a third relatively low pressure reducing regulator whereby decrease of pressure in the source connected to the regulator of said pair adjusted to deliver the higher of said differential pressures to or below the pressure for which the other of said pair of regulators is adjusted, will automatically cause gas to be delivered through the latter regulator from one of the plurality of the alternate sources to which it is connected, the improvement comprising positioning said pair of regulators with their adjusting screws toward each other, mechanical linking means comprising a sleeve connecting the pressure adjusting screws of said pair of regulators, means for rotating said sleeve through an arc whereby the differential adjustment of said pair of regulators may be reversed and reset, and a plurality of valves for said pair of regulators associated with conduit means operable so that either regulator of said pair may be removed and the remaining regulator of the pair connected to any of said alternate sources without interruption of gas flow, said plurality of valves comprising a valve on the inlet side and a check valve on the outlet side of each of said pair of regulators and a by-pass valve between the inlets of said pair of regulators upstream of said valves.

2. A gas flow control system for delivering gas at a substantially uniform predetermined pressure to a consumers line from either of a pair of separate gas sources of higher pressures, comprising a pair of high pressure regulators each having an inlet side and an outlet side, a third relatively low pressure regulator having an inlet side and an outlet side adapted to be connected to said consumers line, means connecting the inlet side of said low pressure regulator to the outlet sides of both of said high pressure regulators, conduits interconnecting the in-

let sides of both of said high pressure regulators with both of said gas sources, and selectively operable valve means included in said conduits and selectively controllable to deliver gas from either of said sources to the inlet side of either of said high pressure regulators, whereby either of said high pressure regulators may be removed from service without interrupting the flow of gas to said consumers line.

3. A gas flow control system for delivering gas at a substantially uniform predetermined pressure to a consumers line from either of a pair of separate gas sources of higher pressures, comprising a pair of high pressure regulators each having an inlet side and an outlet side, conduits separately connecting the inlet sides of said regulators to different ones of said sources, a third relatively low pressure regulator having an inlet side and an outlet side adapted to be connected to said consumers line, means connecting the inlet side of said low pressure regulator to the outlet sides of both of said high pressure regulators, a by-pass conduit interconnecting said first-named conduits to deliver gas from either of said sources to the inlet side of the high pressure regulator to which the source is not separately connected, and selectively operable valves included in said by-pass conduit and said first-named conduits and selectively controllable to effect the delivery of gas through said conduits from either of said sources to the inlet side of either of said high pressure regulators and to cut off the delivery of gas to the inlet side of the other high pressure regulator, whereby either of said high pressure regulators may be removed from service without interrupting the flow of gas to said consumers line.

4. A gas flow control system for delivering gas at a substantially uniform predetermined pressure to a consumers line from either of a pair of separate gas sources of higher pressures, comprising a pair of high pressure regulators each having an inlet side and an outlet side, a third relatively low pressure regulator having an inlet side and an outlet side adapted to be connected to said consumers line, means connecting the inlet side of said low pressure regulator to the outlet sides of both of said high pressure regulators, conduits interconnecting the inlet sides of both of said high pressure regulators with both of said gas sources, selectively operable valve means included in said conduits and selectively controllable to deliver gas from either of said sources to the inlet side of either of said high pressure regulators, whereby either of said high pressure regulators may be removed from service without interrupting the flow of gas to said consumers line, and means including a by-pass conduit connected across said low pressure regulator for delivering gas to said consumers line directly from the outlet sides of either of said high pressure regulators without traversing said low pressure regulator, whereby said low pressure regulator may be removed from service without interrupting the flow of gas to said consumers line.

5. A gas flow control system for delivering gas at a substantially uniform predetermined pressure to a consumers line from either of a pair of separate gas sources of higher pressures, comprising a pair of adjustable high pressure regulators each having an inlet side and an outlet side, a third relatively low pressure regulator having an inlet side and an outlet side adapted to be connected to said consumers line, means including a header commonly connected to the outlet sides of said high pressure regulators for delivering gas from said high pressure regulators to the inlet side of said low pressure regulator, means for adjusting the delivery pressures of said high pressure regulators so that the outlet side gas pressure of one of said high pressure regulators is appreciably higher than the outlet side gas pressure of the other of said high pressure regulators, whereby gas is delivered to said common header through said other high pressure regulator only when the outlet side gas pressure of said one high pressure regulator drops to a value not exceeding the out-

let side gas pressure of said other high pressure regulator, conduits interconnecting the inlet sides of both of said high pressure regulators with both of said gas sources, and selectively operable valve means included in said conduits selectively controllable to deliver gas from either of said sources to the inlet side of either of said high pressure regulators.

6. A gas flow control system for delivering gas at a substantially uniform predetermined pressure to a consumers line from either of a pair of separate gas sources of higher pressures, comprising a pair of adjustable high pressure regulators each having an inlet side and an outlet side, a third relatively low pressure regulator having an inlet side and an outlet side adapted to be connected to said consumers line, means including a header commonly connected to the outlet sides of said high pressure regulators for delivering gas from said high pressure regulators to the inlet side of said low pressure regulator, means for adjusting the delivery pressures of said high pressure regulators so that the outlet side gas pressure of one of said high pressure regulators is appreciably higher than the outlet side gas pressure of the other of said high pressure regulators, whereby gas is delivered to said common header through said other high pressure regulator only when the outlet side gas pressure of said one high pressure regulator drops to a value not exceeding the outlet side gas pressure of said other high pressure regulator, signaling means operated upon the occurrence of a drop in gas pressure in said common header to a pressure less than the outlet side gas pressure of said one high pressure regulator, conduits interconnecting the inlet sides of both of said high pressure regulators with both of said gas sources, and selectively operable valve means included in said conduits and selectively operable to deliver gas from either of said sources to the inlet side of either of said high pressure regulators.

7. A gas flow control system for delivering gas at a substantially uniform predetermined pressure to a consumers line from either of a pair of separate gas sources of higher pressures, comprising a pair of adjustable high pressure regulators each having an inlet side and an outlet side, a third relatively low pressure regulator having an inlet side and an outlet side adapted to be connected to said consumers line, means including a header commonly connected to the outlet sides of said high pressure regulators for delivering gas from said high pressure regulators to the inlet side of said low pressure regulator, means for adjusting the delivery pressures of said high pressure regulators so that the outlet side gas pressure of one of said high pressure regulators is appreciably higher than the outlet side gas pressure of the other of said high pressure regulators, whereby gas is delivered to said common header through said other high pressure regulator only when the outlet side gas pressure of said one high pressure regulator drops to a value not exceeding the outlet side gas pressure of said other high pressure regulator, means for changing the adjustment of said high pressure regulators to increase the outlet side gas pressure setting of said other high pressure regulator to that of said one high pressure regulator and simultaneously to decrease the outlet side gas pressure setting of said one high pressure regulator to the initial outlet side gas pressure setting of said other high pressure regulator, conduits interconnecting the inlet sides of both of said high pressure regulators with both of said gas sources, and selectively operable valve means included in said conduits and selectively operable to deliver gas from either of said sources to the inlet side of either of said high pressure regulators.

8. A gas flow control system for delivering gas at a substantially uniform predetermined pressure to a consumers line from either of a pair of gas sources of higher pressures, comprising a pair of high pressure regulators each having an inlet side and an outlet side, conduits separately connecting the inlet sides of said regulators to

different ones of said sources, a third relatively low pressure regulator having an inlet side and an outlet side adapted to be connected to said consumers line, means including a header commonly connected to the outlet sides of said high pressure regulators for delivering gas from said high pressure regulators to the inlet side of said low pressure regulator, means including a by-pass conduit connected across said low pressure regulator for delivering gas to said consumers line directly from said header without traversing said low pressure regulator, whereby said low pressure regulator may be removed from service without interrupting the flow of gas to said consumers line, one of said high pressure regulators being operative to deliver gas to said common header at an appreciably higher pressure than the other of said high pressure regulators, whereby gas is delivered to said common header through said other high pressure regulator only when the outlet side gas pressure of said one high pressure regulator drops to a value not exceeding the outlet side gas pressure of said other high pressure regulator, and signalling means operated upon the occurrence of a drop in gas pressure in said common header to a pressure less than the outlet side gas pressure of said one high pressure regulator.

9. A gas flow control system for delivering gas at a substantially uniform predetermined pressure to a consumers line from either of a pair of separate gas sources of higher pressures, comprising a pair of high pressure regulators each having an inlet side and an outlet side, conduits connecting the inlet sides of said high pressure regulators to said sources, a third relatively low pressure regulator having an inlet side and an outlet side adapted to be connected to said consumers line, means including a header commonly connected to the outlet sides of said high pressure regulators for delivering gas from said high pressure regulators to the inlet side of said low pressure regulator, said high pressure regulators being provided with outlet pressure adjusting screws arranged in axial alignment, adjustable linking means interconnecting the ends of said adjusting screws for uni-control operation thereof and normally so set that the outlet side gas pressure of one of said high pressure regulators is appreciably higher than the outlet side gas pressure of the other of said high pressure regulators, whereby gas is delivered to said common header through said other high pressure regulator only when the outlet side gas pressure of said one high pressure regulator drops to a value not exceeding the outlet side gas pressure of said other high pressure regulator, and a lever extending outwardly from said linking means and rotatable about the axis of said adjusting screws to change the adjustment thereof so that in response to limited movement of said lever the outlet side gas pressure setting of said other high pressure regulator is increased to that of said one high pressure regulator and the outlet side gas pressure setting of said one high pressure regulator is decreased to the initial outlet side gas pressure setting of said other high pressure regulator.

10. A gas flow control system as claimed in claim 9, wherein said linking means comprises nutted ends for the outer extremities of said adjusting screws and an elongated element provided with an internal opening at each end having a complementary shape to closely fit over and engage said nutted ends, said lever is connected to and projects outwardly from said elongated element, and screw means are provided for connecting said elongated element to said nutted ends of said adjusting screws.
